CLAIM

The ornamental design for a gaming machine cabinet, as shown and described.

DESCRIPTION

FIG. 1 is an isometric view of a gaming machine cabinet, showing our new design;

FIG. 2 is a front elevational view;

FIG. 3 is a left-hand side elevational view;

FIG. 4 is a right-hand side elevational view;

FIG. 5 is a top plan view;

FIG. 6 is a rear elevational view; and,

FIG. 7 is a bottom plan view.

The dashed lines in the figures show the environment of the present design and are not part of the present design.
